ABSTRACT: This invention is an articulator for adjustably supporting dental casts (used in making dentures) in a position corresponding to the actual position of the jaws for which the dentures are to be made. This articulator provides a device whereby the upper casting may be moved vertically relative to the lower casting, may be pivoted relative to the lower casting in the same manner that the human jaws pivot, and may be moved forwardly or backwardly along an axis extending from the front to the rear of the castings. In addition, the castings may partake of any two or all three of the above adjustments, as may be necessary to depict the true occlusal planes of the patient's original teeth.

ATTORNEY

DENTAL CAST ARTICULATOR

OBJECTS OF INVENTION

This invention relates to an articulator for supporting and accurately adjusting dental castings or teeth forms into a position to represent the correct occlusal planes of the dentures in the human jaw so that they will be in the same position and angle that the original human teeth had occupied, so the the dentures, when in place, will permit the denture wearer to maintain the dentures comfortably in his mouth.

A further object of this invention is to provide an articulator for dental casts that is capable of accurately positioning the denture casts in the true position of the original teeth in the jaws, even though one jaw may protrude or recede abnormally of the other.

A further object of this invention is to provide a dental cast articulator wherein the vertical supporting member for the upper casting is in the form of an articulated or jointed rod, which has sections pivotally connected to each other in such manner that the upper cast may be moved forwardly or rearwardly of the lower cast to correctly depict the true relation of the jaws of the patient to each other.

BRIEF SUMMARY OF INVENTION

In brief, the articulator of this invention has baseplates on which each of the upper and lower dental casts are to be secured in the usual manner. An upright rod is mounted in a shaftway in the lower dental casting base and secured therein, vertically adjustable, by a setscrew extending through the side of the shaftway. The upright rod is articulated or jointed in at least three sections, by means of overlapping extending eyes, and pivot bolts extending through the overlapping eyes securely held wingnuts on the bolts. The pivot bolts extend at an angle normal to the axis extending from the front to the rear of the dental castings, and the upper casting is provided with a protruding eye cooperatively pivoted by a bolt and wingnut to a clamp embracing the top section of the articulated rod, so that the upper casting may be elevated or pivoted or both as need to position the upper casting in true and proper relation to the lower casting.

DESCRIPTION OF DRAWING

With the above and related objects in view, this invention consists in the details of construction and combination of parts, as will be more fully understood from the following description, when read in conjunction with the accompanying drawing, in which:

FIG. 1 is a side elevation of the articulator in operative position with an upper and a lower dental cast in position.

FIG. 2 is a view looking at the right of FIG. 1, from the rear toward the front of the dental castings.

FIG. 3 is a top plan view of FIG. 1.

FIG. 4 is a side elevation of the articulated rod in the position when the lower jaw recedes behind the upper jaw.

FIG. 5 is a side elevation of the articulated rod in the position when the lower jaw protrudes beyond the upper jaw.

DETAILED DESCRIPTION OF INVENTION

There is shown at 18 the articulator of this invention, including a lower base 10 to which the lower jaw dental casting 12 is secured in the conventional manner, and an upper jaw dental casting 14 is similarly secured to an upper base 16, together with an articulated upright supporting rod 20 secured to the lower base 10 and articulated supporting the upper base 16. This invention consists of combination of such casting bases 10 and 16 with the articulated upright supporting rod 20. The articulated rod 20 consists of at least three articulated bottom, middle and top sections 22, 24 and 26 pivotally and adjustably jointed and secured together, at a desired angle, by extending overlapping eyes 28 and pivot bolts 30 extending through the eyes 28 and secured in adjusted position by wingnuts 32.

The bottom rod section 22 is adjustably mounted in a shaftway 34 in lower base 10 and is secured therein by a setscrew 36 extending through one side thereof.

The upper base 16 is provided with a horizontally extending eye 38, and a clamp 40 embracing the top rod section 26 is pivotally secured by bolt 42 and wingnut 44 to the eye 38 of the upper base 16.

OPERATION OF INVENTION

10 The dental castings 12 and 14 are secured to or mounted on their respective bases 10 and 16 in the conventional manner. The teeth forms 46 and 48 are properly positioned and in proper occlusal planes to each other, corresponding to the actual desired occlusal planes of the patient's original teeth, and thus of the dental casting when completed by the dentist, by articulating the rod 20 as needed either with straight angles between the sections 22, 24 and 26 as in FIGS. 1, 2 and 3, or at obtuse angles as shown in FIGS. 4 and 5, to the desired degree 15 to properly reproduce the jaw angles and positions of the patient. Then with the wingnuts 32 and 44 and setscrew 36 tightened to maintain the articulated rod in the desired position and thus maintain the dental castings 12 and 14 in proper relation to each other, the articulator 18 with its castings is 20 sent to the dental technician for making the dentures in the usual manner.

ABSTRACT OF DRAWING

30 In the drawings, like numbers refer to like parts, and for the purposes of explication, marshalled below are the number parts of the improved Dental Cast Articulator:

- 10 lower casting base
- 12 lower dental
- 14 upper dental casting
- 16 upper casting base
- 18 articulator
- 20 articulated supporting upright rod
- 22 bottom rod section
- 24 middle rod section
- 26 top rod section
- 28 rod joint overlapping eyes
- 30 pivot bolt through 28
- 32 wingnuts on 30
- 34 shaftway in 10 for bottom rod section 22
- 36 setscrew to 22 in 34
- 38 eye on upper casting base 14
- 40 clamp on 26
- 42 pivot bolt for 40 through 38
- 44 wing nut for 40
- 46 upper teeth forms
- 48 lower teeth forms

Although this invention has been described in considerable detail, such description is intended as being illustrative rather than limiting, since the invention may be variously embodied, and the scope of the invention is to be determined as claimed.

Having thus set forth and disclosed the nature of this invention, what is claimed is:

1. An articulator (18) for an upper (14) and a lower (12) 60 dental casting, the improvement comprising a lower base (10), an articulated upright rod (20), means (34 and 36) securing said articulated rod (20) in said lower base (10), said rod (20) comprising three articulated straight rod sections (22, 24 and 26) means (28 and 30) for adjustably pivoting 65 each articulated rod section (22, 24 and 26) in the same vertical plane to the adjoining section (22 to 24 and 24 to 26) thereof, means (32) for securing said pivoted rod sections in adjusted position, said lower casting base securing means comprising a vertical shaftway (34) in said lower base, the 70 lower section (22) of said rod (20) extending into said shaftway (34), a setscrew (36) extending horizontally into said shaftway 34 against said lower section (22) for securing said rod (20) in vertically adjusted position thereon, said upper casting base securing means comprising an eye (38) extending 75 from said upper casting base (16), a clamp (40) adjustably

3,600,809

3

embracing said upper articulated rod section (26), and means (42, 44) pivotally, adjustably securing said clamp (40) to said eye (38), said pivotal, adjustable securing means comprising a bolt (42) and a wingnut (44) threaded thereon for ready manual adjustment, said bolt (42) extending through said clamp (40) and said eye (38), said articulated rod sections 122, 24 and 26) having extending overlapping eyes (28), said

4

means (28, 30) for adjustably pivoting and securing each articulated rod section in the same vertical plane comprising said extending overlapping eyes (28) of said rod sections, a threaded pivot bolt (30) extending through said overlapping eyes (28), and a wingnut (32) threaded on said bolt (30).
